CLAIM

The ornamental design for positioning brace for saddle
stirrups, substantially as shown and described.

DESCRIPTION

FIG. 1 is a top plan view of a positioning brace for
saddle stirrups showing my new design;

FIG. 2 is a bottom plan view thereof;

FIG. 3 is a front elevational view thereof;

FIG. 4 is a rear elevational view thereof;

FIG. 5 is an end elevational view thereof; and

FIG. 6 is an opposite end elevational view thereof.
